Brass Company, Grand Rapids, Mich., a corpora-
tion of Michigan

Application December 27, 1949, Serial No. 135,244

3 Claims. (Cl. 292—169)

1

This invention relates to a door latch of the type which may be locked against operation from the outer side of a door, and which may be operated from the inner side of the door to effect such locking. The latch is readily operable from the inner side of the door, when the door is locked, by merely turning the knob and the spindle connected to it to open the door. Such latches are generally known as bathroom locks, being readily manipulated manually to lock the door from its inner side. When thus locked, there can be no knob operation and door opening from the outer side of the door. Further, when so locked, upon leaving the bathroom, manually operating the inner knob in the usual manner to open the door automatically releases the lock; though, of course, the lock may be manually released from the inner side of the door, without turning the knob, by reversing the operation used in locking it.

The present invention is directed to a simplification of the latch structure shown in a prior Patent No. 2,420,083, which was issued May 6, 1947, for Inside Locking Latch Construction. Its object and purpose is to make a latch which is more economical to produce, eliminating parts therein, and further to markedly increase ease and economy in assembling the latch whereby there is double economy of latch production, from the lesser number of parts required and the lesser cost of assembly. The latch produced in accordance with the present structural embodiment thereof disclosed in this application is one which is sturdy and durable, is simple in structure and, because of such simplification, has a longer life of service. It is also more efficient in operation for a longer time than previous latches, including the one disclosed in the above mentioned patent.

An understanding of the invention may be had from the following description, taken in connection with the accompanying drawing, in which:

Fig. 1 is a longitudinal vertical section through the assembled latch of our invention with the major portion of the mechanism of the latch disclosed in elevation, and

Fig. 2 is an enlarged perspective view of the inside locking mechanism which is incorporated in the latch structure.

Like reference characters refer to like parts in the different figures of the drawing.

In the disclosed structure of the latch, a housing of thin or sheet metal is provided preferably in two parts. Each of these parts, at its outer portion and for substantially a half of its length, is of semi-cylindrical form as at 1, and at its inner

2

portion is of a channel form, there being a shoulder, as shown in Fig. 1, between the inner end of the semi-circular section 1 and the channel section 2. When the two housing members are placed together the outer portion is of cylindrical form and the inner portion rectangular in cross section, each side of the inner portion having an outwardly pressed rollback housing 3. The inner end of the latch housing is closed by flanges 4 turned inwardly toward each other as shown. The two semi-cylindrical sections 1 are releasably connected together by a sleeve 5 into which the outer ends of the cylindrical housing parts are received and to which the plate 6 is permanently secured. The plate 6 in turn is screw connected or otherwise equivalently connected at the free edge of a swinging door on which the latch is installed. The flanges 4 at the inner end of the housing may be connected by suitable means known in the art and forming no part of this invention. Installation is by boring a hole from the free edge of the door horizontally inward for reception of the housing, and a transverse opening through the door at a distance from the free edge of the door for the passage of a transverse spindle structure or assembly through it and through the rollback housings of the latch. Knobs are secured at the outer ends of the spindles for manual operation to retract the latch bolt.

The latch bolt 7, beveled at its outer portion as shown, is slidable freely through an opening in the plate 6. A rod 8 is permanently connected to the bolt 7 and extends therefrom axially of the housing through the bottom of a sheet metal cup 9. The metal cup 9 is open at its outer side and is provided with an annular flange 9a which, in practice, is against an annular, inwardly extending shoulder formed in the cylindrical portion of the housing. The rod 8, at its inner ends, has a head 10 of a generally frusto-conical form, the smaller diameter of which is inwardly of the larger diameter. A coiled spring 11 of relatively light strength surrounds the rod 8 between the bottom of the cup 9 and the inner end of the bolt 7.

The cup 9 is a part of a retractor for the latch bolt which, in addition, includes two spaced bars 12 located within and at opposite sides of the housing and which extend nearly to the inner ends 4 of the housing. Such bolt has operative connection with rollbacks 13 of conventional structure mounted for rotative movement in the rollback housings 3 at opposite sides of the hous-

ing. Through the rollbacks 13 and rollback housings 3 there passes a spindle of two parts indicated at S and S', the inner ends of the spindles meeting between the rollbacks and such inner ends having a swivel connection so that one may be operated independently of the other. The spindle S at its end outside of the housing may be equipped with a knob or handle for manual operation which, when the latch is installed on a door, will be at the inner side of the door, it being apparent from the bevel on the bolt 7 that a door carrying the latch as in Fig. 1 will be swung about its hinged mounting in a counterclockwise direction when closing the door. The spindle S' will have a like knob or handle for manual operation at its outer end.

A much heavier coiled compression spring 14 has one end bearing against the flange 9a of the cup member 9 and extends lengthwise of the cylindrical part of the housing toward the shoulders therebetween and the channel sections 2 of the housing. At its inner end it bears against a transverse plate 15 of generally disk form which has diametrically opposed lugs 15a located in notches or openings made in the opposed semi-cylindrical sections 1 of the housing adjacent such shoulders. The openings are of dimensions such that the plate 15 has a limited freedom of movement lengthwise of the housing. The central portion of the plate or disk 15 is pressed laterally as indicated at 16, providing a shallow channel paralleling a diameter of the disk and perpendicular to the diameter of the lugs 15a. The web of such channel 16 at opposite ends has slots, as shown in Fig. 2, for the free passage of the retractor bars 12.

The structure thus far described is a complete latch which, when installed on a door, is operable by turning either of the spindles S or S' through the usual and well-known connection of the rollbacks 13 with the retractor but with no provision for locking the latch so as to lock a door in closed position. Such door with the latch structure would latch in closed position when it was closed but would be readily opened from either side thereof. The structure thus far described provides the environment in which the lock structure of the present invention is used.

A lever 17 pivotally bears against the inner surface of the plate 15, and at its inner end portion has a tail piece or arm 18 adapted to engage a roll-back when the lever is rotated to active position. At its middle portion, the lever 17 has an outwardly extending finger 19 which axially engages a central recess formed by an opening in the web of the channel section 16, which thereby laterally positions the lever. The lever 17 also has an outwardly extending arm 20. The free outer end of the arm 20 is inclined at an angle to the vertical, as indicated at 20a, so that when the head 10 on the bolt 8 is moved inwardly in any manner, if such inclined edge 20a is in the path of movement of the inclined sides of the frusto-conical head 10, the lever will be turned clockwise. It is, of course, understood that the disk 15 is slotted laterally with respect to the central opening for the passage of the arm 20 of the lever through it, and for the lever to have a free pivotal movement. The bottom of the cup 9 is also slotted for the passage of the outer end of the arm 20, when, with the parts in the position shown in Fig. 1, by withdrawing the bolt through spindle operation, the cup 9 is moved inwardly to and a short distance beyond the outer end of the lever arm 20.

The lever 17 is provided with a member for manual movement thereof to locking position. Such member is a push bar 21 having an opening through which the inner arm or tail piece 18 of the lever 17 freely passes, the arm having a shoulder 18a located at the outer side of the push bar 21. The bar 21 passes through openings in the opposite sides of the inner portion of the housing, that is, through the channels 2. At its inner side bar 21 has spaced grooves 21a transversely thereof which are alternately positioned in the openings of the webs of the channel sections 2 of the housing, when the push bar has been manually operated to turn the lever to locking position as in Fig. 1, and also when the push bar is moved and through such movement returns lever 17 to a position in which the arms 18 and 20 are substantially parallel to the length of the housing. The shoulder 18a engaging with the push bar 21 and influenced by forcings of the spring 14 through the plate 15 and thence to the lever 17 causes the push bar 21, when its grooves 21a are located in their respective openings through a side of the housing, to move so that said grooves 21a receive the adjacent edges of the openings, thereby maintaining the bar 21 yieldingly against accidental or aimless change of position.

The push bar 21 at its inner end is shaped with a flat transverse section 22 at right angles to the length of the bar. The section 22 has an interiorly threaded opening through it. A rod 23, at its inner end portion is machined to a smaller diameter, leaving a small stem 24 with a continuous groove in the bar around it, and an inner exteriorly threaded short end portion 25, the diameter of the rod and of the threaded inner end 25 being such that the head 25 may be screwed through the opening in the part 22 until it is passed completely therethrough. This provides a loose or lost motion connection between the rod 23 and the push bar 21. Such lost or loose motion connection is required because the bar 23 is slidable or movable only in the direction of its length, it is mounted on the door and accessible at the inner side of the door for such sliding movement, while the push bar 21 in addition to a longitudinal movement, had a lateral or side tilting movement. The connection made permits such lateral or side movement simultaneously with the longitudinal movement of the push bar 21 by force applied thereto, through a straight line movement of the rod 23. The rollback 13 at the outer side of the door, in a flange thereof, has a slot 26 into which the inner end of the arm 18 passes when, by moving the push rod 21 to the position shown in Fig. 1, lever 17 is moved, thus locking the outer rollback 13 and its spindle S' from rotative movement.

It is evident that when a latch of the structure described is installed on a door and the door closed, the person at the inner of the door, by pushing upon the rod 23, may move the push bar 21 to the position shown in Fig. 1, turning lever 17 counterclockwise and locking the outer rollback and the spindle S' against movement. The door accordingly cannot be opened from its outer side. The spindle S and the rollback 13 connected therewith are free to be operated. Upon such operation, the retractor is withdrawn, thereby moving the bolt 7 inwardly to release from its keeper or strike on the door jam to open the door. Such movement moves the head 10 against the inclined or cam edge 20a of arm 20 turning the latch clockwise and moving the inner

end of the arm 18 out of the slot 26, and moving the push bar longitudinally until the notch 21 on the push bar toward the outer side of the door enters the opening through the adjacent side of the housing. Thus, when the door is opened by knob operation at its inner side the lock is released and the door opened as freely as though the lock had not been put in its operative condition. It is also evident that the lock may be released by a pull on the rod 23. It, further, may be released by pushing inwardly on the bolt 7. The lock is thus released in three separate and distinct ways, though in practice the release by pushing inwardly on the bolt 7 would be seldom resorted to except possibly if a child inadvertently locked himself in a bathroom, the bolt could be pushed inwardly by entrance of a thin member of sufficient strength, between the edges of the door and the door jam, against the beveled end of the bolt to thus retract the bolt and unlock the door.

With this structure pivot pins as shown in Patent No. 2,420,083, and other transverse pins are eliminated together with the difficulties of assembling present in such previous structure. Economy of manufacture both in the parts required and in assembly is obtained. Simplification of the structure results in not only economy, but the reduction of parts subject to wear enhances the durability or life of the latch or lock.

The invention is defined in the appended claims and is to be considered comprehensive of all forms of structure which come within their scope.

We claim:

1. In a door latch having a hollow housing, a latch bolt and a pair of independently operable roll-backs, a retractor for said latch bolt connected to both of said roll-backs and operative upon rotation of either of said roll-backs, the improvement in said door latch including: a transverse plate mounted within said housing between said latch bolt and said roll-backs, said plate having a central aperture and a slot laterally disposed from said aperture; a lever pivotally bearing at an intermediate point thereon against an inner surface on said plate and having a first bar extending through said slot toward said latch bolt, said first bar having a bevelled end disposed to be contacted by said latch bolt on retraction thereof to rotate said lever to inactive position, and a second bar extending oppositely from said first bar and disposed to engage one of said roll-backs on rotation of said lever to active position; axially-interengaging projection and recess means on said plate and lever adapted to laterally locate said lever; stop means limiting inward movement of said lever; and manual means for rocking said lever about said point of pivotal bearing.

2. In a door latch having a hollow housing, a reciprocable latch bolt and a pair of independently operable roll-backs, a retractor for said

latch bolt connected to both of said roll-backs and operative upon rotation of either of said roll-backs, a retractor spring operable to bias said retractor outwardly, the improvement in said door latch including: a plate mounted in said housing transversely thereof and bearing against the inner end of said retractor spring, said plate having a central aperture and a slot laterally disposed from said aperture; a lever pivotally bearing at an intermediate point thereof against an inner surface on said plate and having a first bar extending through said slot toward said latch bolt, said first bar having a bevelled end disposed to be contacted by said latch bolt on retraction thereof to rotate said lever to inactive position, and a second bar extending oppositely from said first bar and disposed to engage one of said roll-backs on rotation of said lever to active position; axially-interengaging projection and recess means on said plate and lever adapted to laterally locate said lever; stop means limiting inward movement of said lever; and means for manually rocking said lever about said point of pivotal bearing.

25 3. In a door latch having a hollow housing, a reciprocable latch bolt and a pair of independently operable roll-backs, a retractor for said latch bolt connected to both of said roll-backs and operative upon rotation of either of said roll-backs, a retractor spring operable to bias said retractor outwardly, the improvement in said door latch including: a plate mounted in said housing transversely thereof and bearing against the inner end of said retractor spring, said plate having a central aperture and a slot laterally disposed from said aperture; a lever pivotally bearing at an intermediate point thereon against an inner surface on said plate and having a first bar extending through said slot toward said latch bolt, said first bar having a bevelled end disposed to be contacted by said latch bolt on retraction thereof to rotate said lever to inactive position, and a second bar extending oppositely from said first bar and disposed to engage one of said roll-backs on rotation of said lever to active position, said second bar having an inwardly-facing shoulder; axially-interengaging projection and recess means on said plate and lever adapted to laterally locate said lever; and a manually reciprocable 40 bar mounted transversely of said housing and having an aperture engaging said second bar, said shoulder bearing against the outer surface of said reciprocable bar.
